Park & Peck.
Machine for Making Wadding.
Patented Jul. 10, 1833.

John Park & William J. Pack, of Westmoreland in the County of Ulster and State of New-York.

Sellers Patent.

The schedule referred to in these Sellers Patent, and making part of the same, containing a description in the words of the said John Park & William J. Pack, themselves of their improvement in the art of making Cotton Padding.

To all to whom these presents shall come.

Be it known that we John Park & William J. Pack, of Westmoreland in the County of Ulster & State of New-York, have invented a new and useful improvement in the art of making Cotton Padding, and that the following is a full & exact description of the construction & operation of the said Machine, as invented by us.

We make a frame about three feet in height, and from sixteen to thirty feet in length, the frame may be of any required width, to suit the cards; where it is used, the posts at one end of the frame (which we call the front end) are about two inches higher, than the plates, on the top of these, we place two set of drawing rollers, one & a half inch in diameter which extend from side to side of the frame, these rollers are geared in such manner that the back set has two revolutions to one of the front ones; back of these rollers, on the plates near the posts, we place two rollers of metal or stone, which we call the sizing rollers; the diameters of these rollers may be from four to eight inches; they are placed side by side horizontally in a trough constructed in such manner as to hold the sizing on the outside of each roller & at the same time allow the cotton from the drawing rollers to pass between them downward onto a roller lying a little below the back sizing roller, from this roller it is carried onto a set of rollers on the plates; these rollers are from three

to four inches in diameter & are placed about eighteen inches apart the whole length of the frame and serve as a conveyor, for the wadding from the sizing rollers to the back end of the frame.... These rollers are driven by means of a cord & pulley from the feeding or drawing rollers. Above & below these rollers, we place a number of fans similar to those used on a common dressing frame.... These fans are driven from a shaft lying on the sills of the frame, which we call the drawing shaft; the drawing rollers take their motion from this shaft; the sizing rollers are driven with gear wheels.... From the drawing rollers to supply the sizing rollers with sizing, we place a tub by the side of the frame, near the front end, in which we place a small pump for lifting the sizing into the trough around the sizing rollers.

This pump is driven by means of a cord & pulley from the drawing shaft between the top of the tub & below the rollers under the sizing rollers. We place a trough to gather the surplus sizing if any, and return it into the tub again; we likewise place a pair of rollers at the back end of the frame one above the other, which confines the wadding in such a manner, that it can be raised in a perpendicular position on to a set of conveyors which are framed with two rollers, one of which is placed two or more feet above the last mentioned rollers, the other from four to six feet, in front of the frame, we wind cords around these rollers, from two to four inches apart. These form another conveyor to convey the wadding from the back to the front end of the frame, then driven by means of a cord & pulley from the drawing rollers....

The operation of the above described machine is as follows.... We take a lap from the lap roller of a common cotton carding machine & introduce one end of it between the drawing rollers, from the drawing rollers, it passes between the sizing rollers, from the sizing rollers, it passes into one of the cords which carries it to the back end of the frame.

frame, it is then raised nearly perpendicular onto another set of conveyor rods, which carries it to the front end again, while the wadding is passing from the front to the back, and from the back to the front end of the frame every other part of the machine is in operation.

What we claim as our invention or discovery consists in the applying and proportioning the above described Machinery, generally & especially the passing the cotton between the drawing & sizing rollers in such a manner as to make a continued sheet, which is sized and dried by the operation of the same Machinery.
